(57) **CLAIM**

The ornamental design for a multi-purpose garment, substantially as shown and described.

DESCRIPTION

FIG. 1 is a front perspective view of the first embodiment of the multi-purpose garment showing our new design;

FIG. 2 is a front elevation view thereof;

FIG. 3 is a rear elevation view thereof;

FIG. 4 is a left side elevational view thereof;

FIG. 5 is a right side elevational view thereof;

FIG. 6 is a top plan view thereof;

FIG. 7 is a bottom plan view;

FIG. 8 is the second embodiment of the multi-purpose garment;

FIG. 9 is a front elevation view thereof;

FIG. 10 is a rear elevation view thereof;

FIG. 11 is left side elevation view thereof;

FIG. 12 is a right side elevation view thereof;

FIG. 13 is a top plan view thereof; and,

FIG. 14 is a bottom plan view thereof.

The features of the garment shown in broken lines in the drawings form no part of the claimed design.

1 Claim, 6 Drawing Sheets
